CLAIM

The ornamental design for a pillow, as shown and described.

DESCRIPTION

FIG. 1 is a perspective view of a pillow in accordance with the new design, showing an embodiment of the design with respect to an exemplary king size pillow;

FIG. 2 is a top plan view of the pillow of FIG. 1;

FIG. 3 is a bottom plan view of the pillow of FIG. 1;

FIG. 4 is a front elevation view of the pillow of FIG. 1;

FIG. 5 is a rear elevation view of the pillow of FIG. 1;

FIG. 6 is a side elevation view of the pillow of FIG. 1;

FIG. 7 is an opposite side elevation view of the pillow of FIG. 1, for the side opposite that of FIG. 6;

FIG. 8 is a perspective view of a pillow in accordance with the new design, showing an embodiment of the design with respect to an exemplary standard size pillow;

FIG. 9 is a top plan view of the pillow of FIG. 8;

FIG. 10 is a bottom plan view of the pillow of FIG. 8;

FIG. 11 is a front elevation view of the pillow of FIG. 8;

FIG. 12 is a rear elevation view of the pillow of FIG. 8;

FIG. 13 is a side elevation view of the pillow of FIG. 8; and,

FIG. 14 is an opposite side elevation view of the pillow of FIG. 8, for the side opposite that of FIG. 13.
